UNITED STATES PATENT OFFICE.

FRANK W. HASTINGS, OF BAY CITY, MICHIGAN.

DESIGN FOR A WINDOW-CLEANING IMPLEMENT.

48,062.

Specification for Design.

Patented Nov. 2, 1915.

Application filed April 30, 1915. Serial No. 25,069. Term of patent 14 years.

To all whom it may concern:

Be it known that I, FRANK W. HASTINGS, a citizen of the United States, residing at Bay City, in the county of Bay and State of Michigan, have invented a new, original, and ornamental Design for Window-Cleaning Implements, of which the following is a specification, reference being had to the accompanying drawing, forming a part thereof.

Figure 1 is a front elevation of a cleaning implement, showing my new design; Fig. 2 is a side elevation; and Fig. 3 is a plan view.

I claim:

The ornamental design for a window cleaning implement, as shown.

FRANK W. HASTINGS.
